UNITED STATES PATENT OFFICE.

EDWARD TODD, JR., OF NEW YORK, N. Y., ASSIGNOR TO EDWARD TODD & CO., OF SAME PLACE.

DESIGN FOR A TOOL-HANDLE.

SPECIFICATION forming part of Design No. 23,346, dated June 12, 1894.

Application filed April 18, 1894. Serial No. 508,045. Term of patent 7 years.

To all whom it may concern:

Be it known that I, EDWARD TODD, Jr., a citizen of the United States, residing at New York, in the county of New York and State 5 of New York, have invented and produced a new and original Design for Tool-Handles; and I do hereby declare the following to be a full, clear, and exact description of the same, reference being had to the accompanying 10 drawing, forming a part thereof.

The drawing is a side elevation of a tool handle showing my design, the leading feature of which consists in a series of alternate plain and ornamented sections running obliquely across the handle from one edge to the other.

Both sides of the handle are alike, only one side being shown. One edge A is substan-

tially an ogee curve and the other edge B is a series of scallops corresponding with the sections C, D the former being plain and the latter ornamented. Each section has a bulbous or pear-shaped appearance, being slightly curved and merging into a common surface at the edge A of the handle. 25

This handle is designed for any small tool for which it is suitable.

What I claim as my invention is—

The design for a tool handle, substantially as shown and described. 30

In testimony whereof I affix my signature in presence of two witnesses.

EDWARD TODD, JR.
